UNITED STATES PATENT OFFICE.

FLOYD TROUTMAN ROMBERGER, OF ELIZABETHVILLE, PENNSYLVANIA.

INTERNAL-COMBUSTION ENGINE.

1,189,625.

Specification of Letters Patent.

Patented July 4, 1916.

Application filed January 23, 1916. Serial No. 74,789.

To all whom it may concern:

Be it known that I, FLOYD T. ROMBERGER, a citizen of the United States, residing at Elizabethville, in the county of Dauphin and State of Pennsylvania, have invented 5 certain new and useful Improvements in Internal-Combustion Engines, of which the following is a specification.

My invention relates to improvements in 10 internal combustion engines of the type embodying a rotatable valve or valves, for controlling the entrance and discharge of gas into and out of the cylinders thereof.

An important object of the invention is 15 to provide an engine of the above mentioned character, so constructed, that the leakage of pressure between or about the rotatable valve, from the cylinder, is prevented.

A further object of the invention is to 20 provide an engine of the above mentioned character, which is simple in construction, and highly efficient in operation.

Other objects and advantages of the invention will be apparent during the course 25 of the following description.

In the accompanying drawings forming a part of this specification and in which like numerals are employed to designate like parts throughout the same, Figure 1 is 30 a central vertical sectional view through a cylinder of an engine embodying the invention, and, Fig. 2 is a vertical sectional view taken on line 8—8 of Fig. 1.

In the drawings, wherein for the purpose 35 of illustration is shown a preferred embodiment of my invention, the numeral 10 designates the cylinders of an internal combustion engine, provided with a water jacket 11, as is customary. Mounted to recipro- 40 cate within these cylinders are pistons 12. Extending horizontally above the cylinders 10 are cylindrical valve casings 13, having water jackets 14, in free communication with the jacket 11. One end of this double 45 walled tubular valve casing has a tubular head 13', provided with a stuffing box 14'. The opposite end of the casing 13 is projected beyond the jacket 14 in the form of a screw-threaded flange 15', receiving a cap 50 16'. The valve casings 14 have inlet and exhaust ports 15 and 16 communicating with the upper end of the cylinder, as shown.

In Figs. 1 and 2, a pair of intermediate substantially cylindrical sleeves 30 and 31

are arranged within the valve casing 13 and 55 have ports 32 and 33, in registration with the ports 15 and 16, as shown. These intermediate sleeves may remain stationary or may be moved, such as turned back and forth or rotated. Each intermediate sleeve 60 is split longitudinally, as shown at 34, and is circumferentially resilient whereby it is contractible and expansible. These sleeves have their longitudinally split portions arranged to break joint. Mounted to rotate 65 within the inner sleeve 31 is a tubular valve 35 having a port 36 adapted for registration with the ports 32 and 33 as is obvious. The valve 34 is driven by a sprocket wheel 36 receiving rotation from a sprocket chain 37. 70 The inner and outer sleeves 30 and 31 are held against longitudinal displacement by the tubular head 13' and the cap 16'. The valve 35 projects through the stuffing box 75 14', as shown.

In the operation of the engine, it is ob- 75 vious that one valve 17 will control the inlet of gases into the cylinder 10 and the other valve the outlet of gases therefrom. It is obvious that the invention is in no 80 sense restricted to the employment of two valves for this purpose as one valve may be provided with ports in a suitable manner to serve the function of both valves.

The operation of all other forms of the 85 engine are believed to be obvious in view of the foregoing description.

It is to be understood that the form of my invention herewith shown and described is 90 to be taken as a preferred example of the same, and that various changes in the shape, size; and arrangement of parts may be resorted to without departing from the spirit of the invention or the scope of the subjoined claim.

Having thus described the invention, I 95 claim:

An engine of the character described, comprising a cylinder having a substantially cylindrical double walled valve casing pro- 100 vided with a port communicating with the interior of the cylinder, said valve casing being provided at one end with a tubular head carrying a stuffing box and at its op- 105 posite end with a screw-threaded flange; a cap carried by the flange; a pair of cylindri- 110 cal longitudinally split resilient sleeves mounted one within the other with their lon-

itudinally split portions arranged to break joint and disposed within the valve casing and confined between the tubular head and cap; a tubular valve mounted within the 5 inner sleeve and projecting outwardly through the tubular head and stuffing box; and means to rotate the valve.

In testimony whereof I affix my signature in presence of two witnesses.

FLOYD TROUTMAN ROMBERGER, M. D.
